UNITED STATES PATENT OFFICE.

EMILE PICKHARDT, OF ISLINGTON, MASSACHUSETTS.

DESIGN FOR A GARTER-CABINET.

SPECIFICATION forming part of Design No. 31,726, dated October 24, 1899.

Application filed June 6, 1896. Serial No. 594,628. Term of patent 14 years.

To all whom it may concern:

Be it known that I, EMILE PICKHARDT, a citizen of the United States, residing at Islington, in the county of Norfolk and State of Massachusetts, have invented and produced a new and original Design for a Garter-Cabinet, of which the following is a specification, reference being had to the accompanying drawing, forming part thereof.

10 The drawing is a perspective view of the garter-cabinet.

This design relates to a cabinet in which specimens of the contents of the cabinet may be displayed through portions of faces of the 15 body.

The leading or material feature of the design consists of the ornamentation of certain faces through which the specimens are to be exhibited.

20 The form of the cabinet, including the standard, is that of a standard 110, surmounted by a right prism. Those faces of the prism or body through which the specimens are to be exhibited alternate with other faces. The

25 central portion of each of the former faces is the pane within the boundary line 2. The surface of this pane and that of the portion

3 outside of the line 2 are plane surfaces or parts of a single plane surface. The surfaces 20 of the other faces are plane surfaces. 30 The plane of each face-plate is behind that of the narrow surfaces 4, and the embossed corner-pieces 5 are superimposed on the surfaces 4 and overlap the face-plates. The top of the cabinet presents two plane surfaces 6, 35 inclosed by a margin 60 and separated by a narrow convex surface 61, extending across the top. The edges 62 of the top are in planes a little in front of the corner-pieces 5 and are the crowning surfaces of the faces of the 40 cabinet. The upper surface of the margin 60 is in a plane above that of the surfaces 6, and the ornaments 7 extend above the margin 60 at each corner of the top.

Having thus described my design, what I 45 claim, and desire to secure by Letters Patent, is—

The design for a garter-cabinet, as herein shown and described.

EMILE PICKHARDT.
